UNITED STATES PATENT OFFICE.

CHARLES C. RITZ, OF NEW YORK, N. Y.

DESIGN FOR A BOTTLE.

Application filed January 16, 1926. Serial No. 16,140. Term of patent 14 years.

To all whom it may concern:

Be it known that I, CHARLES C. RITZ, a citizen of the United States of America, residing in the city, county, and State of New York, have invented a new, original, and ornamental Design for Bottles, of which the following is a specification, reference being had to the drawing, forming a part thereof.

In the drawing,

I claim:

The ornamental design for a bottle substantially as shown.

CHARLES C. RITZ.
